CLAMP FOR WIRE STRETCHERS.
APPLICATION FILED SEPT. 3, 1919.

Patented Mar. 29, 1921.

2 SHEETS—SHEET 2.

UNITED STATES PATENT OFFICE.

JOSEPH G. KERR, OF GOODLAND, KANSAS.

CLAMP FOR WIRE-STRETCHERS.

1,373,078.

Specification of Letters Patent. Patented Mar. 29, 1921.

Application filed September 3, 1919. Serial No. 321,350.

To all whom it may concern:

Be it known that I, JOSEPH G. KERR, a citizen of the United States, residing at Goodland, in the county of Sherman and State of Kansas, have invented certain new and useful Improvements in Clamps for Wire-Stretchers, of which the following is a specification.

The object of this invention is to provide a simple and inexpensive device by the use of which fence wires may be securely held while being stretched and secured after stretching. The invention is illustrated in the accompanying drawings and will be hereinafter fully described, the novel features being subsequently particularly pointed out in the appended claim.

In the drawings—

Figure 1 is a perspective view of a clamp constructed in accordance with my invention;

Fig. 2 is a plan view of the same;

Fig. 3 is a plan view of the clamp operatively connected with a wire stretcher;

Fig. 4 is a side elevation, partly broken away and in section, showing a portion of a wire secured by the clamp.

In carrying out the invention, I employ two jaws 1 and 2 which are each provided at one end with an opening 3 to receive links 4 forming part of the means for attachment to the wire stretcher. One link 4 carries a second link 5 while the other link 4 carries a hook 6 adapted to be engaged in the link 5 which is connected by the short chain or cable 7 with the wire stretcher lever 16, the jaws 1 and 2 being drawn together by the pull upon the chain 7 so as to clamp the wire. At the ends remote from the openings 3, the jaws are pivoted together by a bolt or pin 8 inserted through registering openings in the jaws and the jaw 2 is constructed with an offset portion 9 whereby the main portion of the jaw will be in the same plane with the body of the jaw 1, while permitting the ends of the jaws to be disposed side by side and pivotally connected. The opposed edges of the jaws are provided with wire-clamping means which, in the instance of the lower jaw 1, comprises a recess or socket 10 formed in an intermediate thickened portion of said lower jaw and provided with depressions or corrugations 11 in its base and conveniently defined by longitudinal flanges 12 at the sides of the jaw which flanges project above the

upper ends of the corrugations, and serve to center the upper jaw with respect to the lower jaw and prevent lateral displacement thereof, as shown. The upper jaw 2 is provided with a mating clamping member or projection 13 which is adapted to enter between the flanges 12 and is equipped with bosses or teeth 14 adapted to engage in the corrugations or depressions 11 in the under jaw.

In the illustrated embodiment of the invention, the lever 16 carries two anchoring or fulcrum pawls 17 which are pivoted to the lever at opposite sides of the point of attachment of the chain 7. The free ends of the pawls 17 are suitably constructed to engage the free portion of a chain 18 which is wrapped around or otherwise secured to the fence post 19.

The use of the invention will be readily understood. When the jaws are opened or separated as in Fig. 1, a portion of a fence wire 15 may be easily inserted between the clamping portions of the jaws and held against lateral movement by the side flanges 12 or their equivalents. After the wire has been placed in the socket member 10, the upper jaw 2 is brought down upon the same, as shown in Fig. 3, and when force is exerted through the wire stretcher upon the link 5, the connecting members 4, 5 and 6 will be caused to more closely approach each other and the pull exerted upon them will serve to hold the jaws 1 and 2 in close contact with the wire so that slipping of the wire will be positively prevented and it may be drawn taut and then secured while held in a taut condition. After the fence wire has been secured, a release of the tension upon the wire stretcher will permit the members 4, 5 and 6 to slacken, as shown in Fig. 1, whereupon the clamp may be removed from the wire. Should the wire-engaging portions of the jaws become worn through long continued use so as to be no longer efficient, the hook 6 may be easily disengaged from the link 5 so that the jaws may be spread apart sufficiently to permit the corrugations to be increased in depth by filing or any other convenient method. Should either jaw be broken, the bolt can be easily removed and a new jaw substituted.

It will be readily understood that the lever 16 is swung alternately in opposite directions about the oppositely disposed

pawls 17 which serve alternately as fulcrums, the inactive pawl being shifted manually along the chain 18 to engage the same at a point nearer the post 19.

5 My device is exceedingly simple in the construction and arrangement of its parts and may be produced at a very low cost and in use will be found highly efficient for the purpose for which it is designed.

10 Having thus described the invention, what is claimed as new is:

A clamp for wire stretchers comprising a pair of pivotally connected jaws, one of said jaws being substantially straight from 15 end to end with its greatest dimension entirely within a single plane and the other jaw being substantially straight through

nearly its entire extent and laterally offset at its pivotal end whereby the pivotal ends of the jaws may be disposed side by side 20 to receive a transverse pivot and the wire to be stretched may be disposed longitudinally upon the edge of the first mentioned jaw without bending, the inner longitudinal edges of said jaws being provided with intermeshing corrugations and one of the jaws being formed with spaced longitudinal side flanges projecting above the ends of the adjacent corrugations and adapted to overlap the side walls of the mating jaw when said 30 jaws are closed, and a connection between the free ends of the jaws.

In testimony whereof I affix my signature.
JOSEPH G. KERR. [L. S.]
